FOOT KNEADING RUGS

Leonard W. Wright, Everett, Wash.

Application April 4, 1955, Serial No. 498,821

2 Claims. (Cl. 128—25)

The present invention relates to a foot kneading rug which may be of any desired size and serves to invigorate feet kneaded by treading bare upon such a rug.

The most important object of the invention is to provide a rug having a construction which will exert firm pressure in localized areas upon a bare foot treading upon the rug, thus to knead therapeutically the flesh and muscles of the foot bottom so as to restore the range of motion in the feet and legs, while at the same time the foot support is yielding and smooth so that the pressure will not be localized to a point in any instance, and the pressure on the foot as a whole will not be harsh.

Another object is to provide a foot kneading rug having a construction incorporating components the design and arrangement of which can be altered readily so as to provide a foot kneading tread having characteristics considered most desirable for a particular purpose or preferred by a given user.

A further object is to employ a foot kneading rug construction of simple character which can be fabricated economically, and which will be very sanitary and durable. Moreover, such a rug can be produced in any desired size.

A preferred type of foot kneading rug, as shown in the drawings and capable of accomplishing the foregoing objects, includes a base pad of sponge rubber on which hard buttons are mounted in distributed arrangement. Such buttons are of spherical segmental shape of a thickness approximately equal to the thickness of the sponge rubber pad and located in regular arrangement. The composite surface formed by the rounded upper portions of such hard buttons and the intervening soft depressions formed by the exposed upper surface of the pad is covered intimately by a cover membrane forming the rug tread.

Figure 1 is a fragmentary plan view of a portion of the foot kneading rug.

Fig. 2 is an enlarged top perspective view of a corner fragment of the foot kneading rug.

Figure 3 is a fragmentary vertical sectional view through a portion of the rug on line 3—3 of Figure 2.

Figure 4 is a vertical sectional view through a portion of the foot kneading rug shown in use.

In the past foot kneading rugs have been proposed of uneven contour, but of unvarying density and with little or no resilience. If the protuberances of such a rug are made sufficiently high to produce desirable therapeutic kneading action on the bottom of a foot, their action on the foot is so harsh that the foot is made sore and the user will soon discontinue its use in many cases. On the other hand, if the bumps of the surface are sufficiently low so that the effect on the foot is not excessively harsh as the foot treads on the rug, the arch of the foot which most needs the kneading action will not be worked effectively, and the desired therapeutic value is not obtained.

In some rugs for kneading the feet proposed heretofore, granular filling material has been employed which is shiftable, and consequently produces an uneven surface of haphazard character so that the kneading effect on the

2

foot is unpredictable, and again the most beneficial therapeutic action cannot be obtained from the use of such a rug. In other instances foot massaging rugs or appliances have incorporated knobs which serve almost solely to support the foot, so that such knobs themselves must be made resilient in order to avoid an action which is too harsh on the foot. For that reason such protuberances do not afford the desired localized and rather concentrated pressure produced by the present invention which accomplishes the kneading action in various portions of the sole of the foot.

A foot sole is very sensitive, and if a person steps on a hard knob or lump which is supported by a hard base, the concentrated pressure thus produced on the foot is very uncomfortable even though it may be healthful. An example of such an instance is stepping on a stone on the ground. If a foot kneading rug attempts to duplicate uneven ground, therefore, the portions of the foot arch will not receive the kneading action which they should, or the action as a whole will be excessively unpleasant.

While as mentioned it is most important that the arch portion of the foot receive adequate kneading, the proper kneading action cannot be accomplished by supporting the foot on a single resilient protuberance engaging only the foot arch. Such pressure is not sufficiently concentrated or localized to produce the proper kneading action, and such pressure is exerted principally on only one region of the foot arch instead of being applied first to one portion and then to another portion of the arch. To obtain the proper kneading action it is important that the pressure be applied in quite a small spot, but if the foot is supported by such pressure in one spot alone, the pressure will be too uncomfortable.

To avoid the discomfort of unyielding pressure concentrated in a small spot on the foot heretofore, foot kneading devices have increased the area of contact of the foot with a protuberance and have made the protuberance resilient. As a result the most beneficial localized kneading action is not obtained. The foot kneading rug of the present invention, on the contrary, produces the desired result by avoiding all possibility that the foot will be supported by only one or two protuberances at any time, but, on the contrary, the protuberances are located sufficiently close together that the foot will always bear on several protuberances. Also, while high enough to massage or knead the highest portion of the foot arch, the protuberances are low enough so that usually a portion of the foot is supported by depressions between protuberances.

In order to apply localized firm pressure to the sole of the foot without excessive discomfort an important feature of the foot kneading rug is to make the protuberances hard, but to mount them resiliently and to make the intervening depressed portions of the rug tread between the protuberances resilient, so that at the locations where pressure is to be applied to the foot particularly it will be firm concentrated pressure, but support of the foot will be assisted by yielding substantially uniformly distributed pressure on other parts of the foot. These general characteristics of the foot kneading rug and their importance should be kept in mind in considering the following detailed description of the preferred rug construction shown in the drawings.

A foot kneading rug having the characteristics discussed above may be composed of a base pad 1 of any area. Such base pad is made of resilient material such as sponge rubber and is sufficiently thick to afford a substantial amount of resilience as a support for hard protuberances and which will yield sufficiently by application of foot pressure in the depressions between the protuberances to distribute the supporting pressure substantially uniformly over the foot portions bearing on the depressions. To accomplish this result the base pad

3

should be from one-quarter to one-half of an inch in thickness.

On the resilient base pad 1 are mounted buttons 2 of hard material, that is, material which does not yield easily to pressure but is firm and solid, although not entirely unyielding or rigid. Such buttons, therefore, may be made of plastic material such as hard rubber or nylon, molded to shape. The knobs on the rug tread produced by such buttons should be rounded, and consequently such buttons may be made of spherical segmental shape. Also, it is preferred that the rise of such knobs be approximately equal to the thickness of the base pad, and such buttons may therefore be made one-quarter to one-half inch thick. The width of the knobs at the base should be several times as great as their thickness and conveniently may be one and one-half inches to two inches in diameter.

The foot kneading rug is used by treading upon it with bare feet as in walking, and the best therapeutic effect on the feet is obtained by shifting the feet about as they step on the rug, so that all parts of the soles of the feet will be kneaded. Consequently, the protuberances should be distributed substantially evenly over the rug surface and conveniently may be arranged in rows as shown in Figure 1. It is preferred, however, that the buttons in adjacent rows be arranged in staggered relationship as shown. The spacing between adjacent buttons is approximately equal to the width of the buttons or may be somewhat less, such as from one inch to one and three-quarter inches, but is at least a plurality of times as great as the thickness of a button.

The maximum width of an adult's foot is in the range of two and one-half to three and one-half inches, and consequently the width of the foot will always engage two buttons arranged transversely of the foot at some location because of the staggered arrangement of the rows of knobs. Moreover, an adult's foot is from eight to twelve inches in length, so that the foot will always engage at least three knobs over its length, as shown in Figure 4, and frequently will engage four buttons. Consequently, the foot almost invariably will step on at least five knobs and a large foot may contact at least parts of as many as nine or ten knobs in some instances. Moreover, almost invariably portions of the foot will engage and receive some support from the depressions between the buttons or knobs.

To produce a sanitary smooth uniform tread surface which may be attractively colored, a membrane 3 is placed as a cover over the upper rounded surfaces of the buttons 2 and the intervening depressions formed by the surface of the base pad 1 exposed between the buttons. Because of the type of material used for this cover preferably being a thin sheet of rubber, it will drape to follow the contour of the pad and buttons faithfully into intimate contact with them and will not itself afford any supporting pressure to the foot except such as is transmitted through it from the base pad or button which the particular portion of the membrane overlies. Such membrane, however, covers all joints so as to eliminate cracks and crevices and is readily washable and resistant to injury by cleaning or disinfectant materials.

It will be evident that a foot treading on the undulated surface of the foot kneading rug described above will have exerted upon it at several locations, such as five to

4

ten, firm kneading pressure of localized character produced by the knobs formed by the buttons 2 beneath the cover membrane 3. While the contact of the membrane with the foot is soft and gentle, the pressure is firm be-

cause of the hard character of the button 2, which is not appreciably deformed by the weight of the foot, so that the pressure in each instance will remain localized rather than spread and diffused, although the button itself will be moved by the pressure of the foot on it because it is mounted on a yielding, sponge rubber pad. At no location, however, will the pressure be harsh, first because the foot is not supported by pressure at only one or two locations, but the bearing is distributed over several locations as discussed. Second, the yielding support of the buttons afforded by the resilient base pad will enable such buttons to yield in height and to tilt to some extent so that the pressure exerted by the several buttons is reasonably equalized. Third, additional portions of the foot not at the time being subjected to kneading action may receive some support with a distributed bearing from depressions formed by the base pad between the knobs.

The result of treading at random on the foot kneading rug described is that the entire sole of the foot will be kneaded by the shifting application of firm pressure at several locations on the sole of the foot without appreciable discomfort. The invigorating exercise thus received by the foot may be repeated frequently without appreciable discomfort.

I claim as my invention:

30 1. A foot kneading rug comprising a sponge rubber base pad, and individual buttons of material substantially harder than said base pad, mounted on and distributed over said base pad and having rounded upper portions, the width of each button at its base being several times 35 as great as its maximum thickness, the thickness of said base pad being at least substantially as great as the maximum thickness of a button to support said buttons yieldingly and tiltably, and said buttons being spaced apart a 40 distance at least a plurality of times as great as the maximum thickness of a button.

2. A foot kneading rug comprising a sponge rubber base pad, individual buttons of material substantially harder than said base pad, mounted on and distributed over said base pad and having rounded upper portions, the width of each button at its base being several times as great as its maximum thickness, the thickness of said base pad being at least substantially as great as the maximum thickness of a button to support said buttons yieldingly and tiltably, and said buttons being spaced apart a 50 distance at least a plurality of times as great as the maximum thickness of a button, and a membrane covering the upper surfaces of said buttons and the surface portions of said base pad between said buttons and draped into intimate contact both with the rounded upper surfaces of said buttons and with the portions of said base pad forming the depressions intervening between said buttons.
